Application August 30, 1937, Serial No. 161,622

34 Claims. (Cl. 250—36)

The present invention relates to electric oscillators, and more particularly to oscillators comprising amplifiers, such as vacuum tubes.

Various devices are in use or have been proposed for obtaining an electrical circuit which is self-oscillatory. The well-known Colpitts and Hartley circuits are typical examples, and many variations or modifications of these or similar circuits are widely used. Such circuits can usually be adjusted to provide an output wave-form which is reasonably close to a sinusoid. In general, however, these circuits are all characterized by the fact that inductance is a necessary part of one or more of the circuit elements in order to obtain the sinusoidal wave-form.

Oscillators employing resistances and capacitances only, but no inductances, are also used. Multivibrators and cathode-ray-oscillograph timing oscillators, or sweep circuits are typical illustrations. A general characteristic of such circuits, however, is a saw-tooth, or irregular, wave-form departing widely from a theoretical sinusoid and containing a large number of harmonics of the fundamental frequency, said harmonics being of appreciably higher amplitude than would be considered satisfactory for a sinusoidal oscillator.

A chief object of this invention is to provide a simple and satisfactory means of obtaining an oscillator which will provide a sinusoidal output voltage, but which does not contain any inductances as necessary circuit elements in order to obtain this sinusoidal wave-form. Other important features of the invention are the ease with which the frequency of the oscillations may be controlled and the practical suppression of all harmonics, as well as extraneous voltages, hum, etc., picked up by or generated by the circuit elements, vacuum tubes, etc.

Other and further objects will be explained hereinafter and will be particularly pointed out in the appended claims.

The invention will now be explained in connection with the accompanying drawings, in which Fig. 1 is a diagrammatic simplified view of circuits and apparatus arranged and constructed according to the present invention; Fig. 2 is a similar view of a modification; Fig. 3 is a diagrammatic view illustrating one form of degeneration network; Figs. 4 and 5 are similar views illustrating other forms of degeneration network; Fig. 6 is a view similar to Fig. 1 of a further modification; Fig. 7 is a diagram illustrating a response curve that is representative of many prior-art types of networks, including the hereinafter described

degenerative network; Fig. 8 is a similar diagram illustrating a response curve in accordance with the present invention; Fig. 9 is a diagram illustrating a preferred embodiment of the invention; Fig. 10 is a view similar to Fig. 7 of a further response curve; and Fig. 11 is a view of a further modification.

The response curve shown in Fig. 7, showing the relation between the output voltage and the frequency, is representative of many types of networks, including some combinations of resistance, capacitance and inductance, or mechanical, piezoelectric or magnetostriction devices. The characteristic feature of a curve of this type is that a single frequency or band of frequencies is cancelled out practically entirely, while a reasonable degree of transmission is obtained at other frequencies. In other words, such a device is a form of band-elimination filter.

Such a characteristic can be obtained in a network using only resistances and capacitors such as, for instance, the Wheatstone bridge, including the Wien bridge, and a parallel-T or bridged-T network. The Wien bridge, for example, illustrated in Fig. 3, is provided with resistors 49, 50, 51 and 52 in its respective arms, and capacitances 54 and 55 respectively in series with and in shunt to the respective resistors 52 and 51. The resistors 49 and 50 are preferably fixed and the resistors 51 and 52 are variable. The parallel-T network consists, as its name implies, of two T networks connected in parallel, as illustrated in Fig. 4, comprising only resistances 3, 4 and 5 and condensers 6, 7 and 8, since this is a convenient form of such a network, but inductances may also be included if desired. The particular T network shown in Fig. 4 has certain desirable characteristics which will be discussed later.

A bridged-T network may comprise only a single T network as, for instance, the circuit elements 5, 6 and 7 of Fig. 5, but with another impedance connected directly in shunt with the two series arms 6 and 7. This is illustrated in Fig. 5, the impedance connected between the opposite terminals of capacitances 6 and 7 being represented by the coil 166. It will be understood that the bridged-T, like the parallel-T, network is not restricted to resistors and capacitors. The elements of both networks may comprise any combination of impedances, including inductors.

The desired characteristics for a selective circuit in accordance with the present invention, as previously outlined, may be practically the inverse of that shown in Fig. 7; that is, the circuit

should respond to a single frequency or a narrow band of frequencies and should attenuate or eliminate frequencies outside of this range, so as to yield a response curve somewhat of the character illustrated in Fig. 8.

In accordance with a principle of this invention, therefore, a circuit having the characteristic shown in Fig. 7 may be combined with suitable auxiliary apparatus so that the net over-all characteristic shall be as shown in Fig. 8. The inverse of the usual characteristic of the curve is thus obtained, a band-suppression network being employed to produce a band-pass system.

This may be effected in any desired way, as, for example, is diagrammatically illustrated in Fig. 1. The amplifier 1 there diagrammatically illustrated may be of any desired type, providing an amount of gain, the importance of which will be discussed hereinafter. The input terminals of the system, shown as 3 and 4, are normally connected together through an impedance, or directly. For instance, if the system is functioning as a band-pass or selective amplifier a source of energy may be connected to terminals 3 and 4. If the system is functioning as an oscillator, as hereinafter set forth, terminals 3 and 4 may be connected together directly, and sufficient regeneration provided in the circuit to cause oscillation to take place. The amplifier is designated by 7 in Fig. 2. It is shown provided with input terminals 102 and 104, connected to its input circuit, and output terminals 106 and 108, connected to its output circuit. In Fig. 1, the terminals 102 and 104 are shown connected by conductors 110 and 112 to the output circuit of a network 2, as hereinafter more fully described. The terminals 106 and 108 may similarly be connected by conductors 114 and 116 to the input circuit of the network 2. The conductors 114 and 116 may also be connected to terminals 5 and 6, which thus constitute the output terminals of the system. These output terminals are represented in Fig. 2 at 10, 11.

The said network 2 is connected so as to feed back energy degeneratively from the output circuit of the amplifier to its input circuit. To this end, the input of the feed-back network 2 is shown connected by conductors 118 and 120 to the output circuit of the amplifier 1, and the output of the network is connected to the input circuit of the amplifier.

The transmission characteristics of the feed-back network 2 are similar to those shown in Fig. 7, so as to provide maximum attenuation or zero transmission or coupling at that frequency or frequencies where it is desired that the system as a whole shall provide maximum transmission. At other frequencies, which the amplifier would normally pass, the network provides a certain amount of transmission and the voltage obtained from the network is fed back to the amplifier input, so that it has a phase reversal with respect to the voltage originally between the terminals 102 and 104, thus reducing the effective gain of the amplifier. By phase reversal, it is intended to denote a shifting of the phase between 90 degrees and 270 degrees. At the frequency or frequencies where the degenerative network provides zero or very low transmission or coupling, the net effective gain of the amplifier is at its maximum or near its maximum, respectively. The result is that the transmission characteristic of the system as a whole has a general characteristic as shown in Fig. 8. It will be seen that the difference in

transmission of the system between the frequencies of maximum and minimum transmission, which characteristic may be defined as the maximum suppression of the system, depends upon both the gain of the amplifier and the transmission characteristics of the degeneration network. The effect of shifting the amplifier gain is to change appreciably the transmission at those frequencies where the transmission is greatest with only a comparatively minor change in the transmission where it is at a minimum, thus modifying the selectivity curve and changing the maximum suppression.

In accordance with the present invention, therefore, selectivity is obtained in an amplifier with the aid of a network which may, but does not necessarily, contain resistances and capacitances only, but without introducing loss in the normal transmission of the system, at the frequencies of maximum transmission.

It is well known that an electrical amplifier can be made to produce sustained oscillations if the output circuit is properly coupled to the input circuit. If the amplifier is sharply selective to a single frequency—that is, if its response is at a maximum at a single frequency—it will tend to oscillate at that frequency.

In Fig. 1, the network 2 has such characteristics as to produce degeneration, in that the output of the amplifier is fed back to the input with such a phase shift that the effective gain of the system is reduced. This degeneration network, however, is designed to have a null point at a certain predetermined frequency—that is, its transmission at this frequency is practically zero, as described above in connection with Fig. 1,—and, accordingly, at this frequency practically no degenerative voltage is applied to the input of the amplifier. Accordingly, at said frequency, the system as a whole provides practically the complete gain of the amplifier. Since the degeneration network may consist of resistances and capacitances only, as will be described later, the system as a whole functions as a selective amplifier, as described above in connection with Fig. 8, although no inductances need be employed.

By varying the elements of the degeneration network it is possible to vary the frequency to which the system is selective. In common with other selective amplifiers this amplifier can be made to oscillate at its selective frequency if a sufficient amount of regenerative coupling exists between the output and the input. Fig. 2 shows such an arrangement, consisting of the amplifier 1, the degeneration network 2, which two units comprise the selective amplifier, plus a regeneration network 3. The characteristics of this network are such that a regenerative voltage is fed from the output of the amplifier back to the input at the frequency where the degenerative network 2 provides no degenerative voltage. The characteristics of the regenerative network may be selective—that is, it may provide regenerative feed-back only at this frequency—or the network may be substantially aperiodic, so that regenerative feed-back takes place through this network over a wide range of frequencies. An obviously necessary condition is that the regenerative feed-back shall be small compared to the maximum degenerative feed-back. In actual practice, best operating conditions are generally found to be when the regenerative feed-back is only slightly larger than the amount necessary to provide sustained

5 oscillations. Consequently, the degenerative feed-back at frequencies a reasonable distance from the oscillation frequency is so large compared to the regenerative feed-back that suppression of harmonics, internal amplifier noise, etc., is obtained. To this end, the amplifier output circuit should be degeneratively coupled to its input circuit at frequencies located above the oscillatory frequency by one octave or more, 10 if harmonic suppression is to take place.

10 The two networks 8 and 9 may, of course, be considered as a single network which provides regenerative feed-back at the frequencies where oscillations are desired and degenerative feed-back at other frequencies. The single network 2 of Fig. 1 may be such a network, or it may be replaced by such a network. Not only may the two networks 8 and 9 be considered as one, but one of the simplest ways of constructing an 15 oscillator of this type includes the use of a single physical network for the purpose, as will be described later on in this specification.

20 A characteristic common to practically all vacuum-tube oscillators is that regeneration takes place at the oscillation frequency. An important feature of the present invention, on the other hand, is that degeneration takes place at other frequencies than the oscillation frequency, being sufficiently great at twice the oscillation 25 frequency and higher frequencies so that harmonics of the oscillation frequency are effectively suppressed. Many networks which may conveniently be used for the purpose provide also degeneration at lower frequencies, so that hum 30 generated or picked up by the amplifier or other low-frequency disturbances are also suppressed. The degenerative action is also effective in lowering the general noise level obtained from the 35 amplifier.

40 A further feature of this invention is that a suitable degenerative network may be made up of resistances and capacitances only, thus eliminating the need for any inductances. The same is true regarding the amplifier itself and the 45 regenerative system, so that, if desired, the complete oscillator need contain no inductances. In spite of this fact, the wave-form may be practically a pure sinusoid. Furthermore, the frequency may be adjusted by varying resistances 50 or by varying capacitances, or both. For many purposes the ability to change frequency by merely varying or switching resistances is a distinct advantage from the standpoints of convenience, cost, and ease of manufacturing. The 55 amplifier may be of any type operating on the vacuum-tube, electro-mechanical, or other principles. Since the harmonic suppression depends upon the degenerative action, however, the harmonic distortion in the output wave-form 60 will decrease as the amplifier gain is increased, providing the degeneration network remains fixed and the regeneration network is adjusted, as previously described, to provide sufficient but not excessive regeneration. Experience has 65 shown that an oscillator of this type comprising a three-stage amplifier using commercially available vacuum tubes will provide nearly the full rated output of the last tube in the amplifier with a distortion of a few tenths of a per cent. Obviously, such a system compares favorably with more conventional types of oscillators employing inductances.

70 In actual practice, it is frequently desirable to use an amplifier in which the phase between the 75 input and output circuits is reversed, so that

provision for such phase reversal does not have to be made in the degeneration network. Such an amplifier is easily obtained by employing three vacuum-tube stages. A further refinement is the use of a direct-coupled amplifier in which the phase shift, even at very low frequencies, is not of serious importance, thus simplifying the design of the degenerative and regenerative systems.

Regarding the degeneration network, this may 10 be practically any type of network which provides a reasonably sharp null balance. Since there are a great number of filter and bridge circuits which provide zero or very low transmission at a single frequency or over a band of 15 frequencies, it is obvious that the invention covers a large number of possible circuit arrangements. Figs. 3 and 4 show two systems employing common types of resistance-capacitance networks for the inverse feed-back systems, and a 20 third type is shown in Fig. 5. In Fig. 3, the inverse feed-back system is illustrated as comprising the before-mentioned Wien bridge. Circuits of this type are widely used for measuring frequency, in which application the suppression of a 25 single frequency or narrow band of frequencies is important. In this use of the Wien bridge, however, the combination with the amplifier and associated apparatus provides an over-all response characteristic which is at a maximum at 30 that frequency to which the bridge is balanced. In a circuit of this type, the response characteristics are determined by the relative values of 35 the resistances and the condensers. The characteristics of the network may be varied by varying all or some of these components.

As illustrated in Fig. 3, the two opposite vertices 122 and 124 of the bridge may be respectively connected to the conductors 110 and 112. The output circuit of the Wien bridge is 40 thus connected to the input circuit of the amplifier. The vertices 122 and 124 may be directly connected to the amplifier input circuit by the conductors 112 and 110, or a transformer 210 may be interposed. The other two opposite 45 vertices 128 and 130 are similarly shown respectively connected by conductors 132 and 134 to the secondary winding 136 of a transformer 40 the primary winding 138 of which is connected by the conductors 114 and 116 to the amplifier output terminals 106 and 108, but these vertices 128 and 130 may be directly connected to the terminals 106 and 108 without the aid of the transformer 40. The output circuit of the amplifier 50 is thus connected to the input circuit of the Wien bridge.

The coupling of the degenerative coupling means, which, in this case, is the Wien bridge, is substantially zero at the predetermined single frequency in question, as is true with all networks having an exact null or zero at balance. 60 The coupling transformers 40 and 210, if used, merely provide the proper balanced-to-ground circuits for the bridge.

Fig. 4 represents an improvement over the 65 circuit shown in Fig. 3 in that the degeneration network consists of a three-terminal network having one terminal 140 common to both its input and its output circuits. The terminal 140 is shown connected by a conductor 142 to the terminal 108 and by a conductor 144 to the terminal 104. One of the other two terminals of the network is shown at 146, connected by a conductor 148 to the terminal 106. The third terminal of the network is shown at 150, connected by a 70 75

conductor 152, to the terminal 102. The particular three-terminal network shown is the previously described parallel-T network, having a characteristic similar to the Wien bridge of Fig. 3, and the frequency of zero transmission may be varied by shifting the resistances 3, 4 and 5, or the condensers 6, 7 and 8 or all six components.

There are several advantages of a system of this type which should be noted. In the first place, if the degeneration or inverse-feed-back network provides complete suppression at a certain frequency, the amplifier gain is normal at that frequency and not affected by the network. Accordingly, if an adjustable network is used so that its zero transmission frequency is adjustable and if the network is so designed and constructed that practically complete suppression is obtained at any frequency to which it is adjusted, the sensitivity of the amplifier to that frequency will be the same as the sensitivity of the amplifier to the same frequency when the network is not used. It is, accordingly, a relatively simple matter to obtain practically constant sensitivity over a wide frequency range by merely using an amplifier with practically constant gain over that range and a feed-back network which gives practically complete suppression at the passed frequency. Of course, if the amplifier characteristic is not flat over a wide range, or if the feed-back network does not give complete suppression, one of these characteristics may be made to balance the other. It should also be noted that since the feed-back network operates directly into a grid circuit, as illustrated in Fig. 9, or into a high-impedance circuit, and may consist itself of high impedances, no appreciable amount of power need be drawn from the amplifier output by the feed-back system.

According to the preferred embodiment of the invention illustrated in Fig. 9, the amplifier is of the three-stage direct-coupled type, the stages being represented by vacuum tubes 12, 14 and 16, each comprising a cathode 156, a grid 154 and an anode or plate 158. The input circuit of the amplifier may be traced from the conductor 152, connected to the output circuit of the parallel-T network, to the terminal 102, and thence to the grid 154 of the tube 12; and from the grid 154 to the filament or cathode 156, a resistor 22 and a condenser 23, in parallel, to the terminal 104; and by way of the conductor 144 to the output circuit of the parallel-T network. The tube 12 is provided with an output circuit extending from its plate or anode 158, by way of a conductor 160, and through a resistor 13, to a plate battery 24, and thence, by way of a conductor 162, to the filament 154. The input circuit of the second stage 14 of the amplifier is shown connected across the resistor 13, and its output circuit is provided with a similar resistor 15 across which the input circuit of the third stage 16 is connected. The output circuit of the amplifier extends from the plate or anode 158 of the tube 16, by way of a conductor 164, to the terminal 106; and through a resistor 17 to the battery 24, and the terminal 108. Each grid 154 of each tube except the first is galvanically or directly connected to the anode of the preceding tube.

This output circuit is coupled to the input circuit of the parallel-T network, as before described.

The connection from the cathode 156 of the tube 12 to the resistor 22 is shown as variable, thus to render it possible to vary the gain of the amplifier, thus to adjust the width of the band

of frequencies to which the system is selective. Varying the gain of the amplifier changes the selectivity of the system by changing the ratio of the voltage obtained from the feedback network to the voltage obtained from the source of energy at frequencies other than that to which the network balances. The same result may be arrived at by varying a potentiometer, as illustrated and described in a copending application Serial No. 161,621, filed by the applicant of even date herewith.

An amplifier of this type is not necessary, but the particular arrangement shown is used since the phase shift at low frequencies between the grid 154 of the first tube 12 and the plate 158 of the last tube 16 is always between 180 and 270 degrees. This simplifies the design of the feed-back circuit. Any other type of amplifier can also be used, however, it being merely necessary to keep the total phase shift through the amplifier and the feed-back circuit such that a serious amount of regeneration does not take place. That is, for any frequency for which the amplifier gain is greater than the attenuation in the feed-back network the total phase shift should be between 90 and 270 degrees in order to provide proper degeneration, excepting, of course, in the neighborhood of the oscillation frequency. The term "phase reversal" will be employed to indicate such a phase shift of the network. For these reasons, an amplifier comprising an odd number of stages is frequently desirable and the direct-coupling feature prevents undesirable phase shifts, even at very low frequencies.

The amplifier shown is battery-operated at 24, but, obviously, any suitable power-supply equipment could be used. The heaters or filaments 156 of the tubes must, of course, be operated from suitable batteries or transformers.

The parallel-T network enclosed within the dotted line marked 212 comprises a feed-back circuit of the type shown in Fig. 4. The particular arrangement shows the resistances 3, 4 and 5 variable, and ganged together for operation by a single control, as is illustrated more particularly in the said copending application. The output of the network 212 is fed back into the amplifier 1 by means of the conductors 144 and 152. The over-all transmission characteristic of such a system is shown in Fig. 8.

The parallel-T network, including resistances and capacitances only, is shown in the preferred embodiment of the invention of Fig. 9, because this particular type of network is extremely useful at audio frequencies. One condition of balance for such a network is obtained when capacitance 6 equals capacitance 7, each equaling one-half of capacitance 8, when resistance 3 equals resistance 4, each resistance 3 and 4 equaling two times resistance 5, and when the frequency is such that the reactance of capacitance 6 is equal in magnitude to resistance 3. This condition of balance for the parallel-T network, as shown in Fig. 9, results in very convenient values for the circuit elements in this network. Obviously, this combination of values lends itself readily to simultaneous operation of the resistances or the condensers by means of a common control. A convenient method for varying such a network over wide ranges at lower frequencies is to employ three variable resistances which are operated by a common control, as illustrated in the said copending application. By switching various sizes of condensers into the

circuit as components 6, 7 and 8, the frequency to which the system is selective may be varied in steps. At higher frequencies, it is sometimes desirable to use variable condensers, which may 5 or may not be connected to a common shaft, and to keep the three resistors fixed, or to vary them in steps by means of a switch. At higher frequencies, a bridged-T network is sometimes more satisfactory than the double-T network on the 10 basis of manufacturing costs and ease of control.

Obviously, the frequency to which this system is selective may be varied by varying the elements in the parallel-T network. A convenient arrangement at lower frequencies is continuously 15 to adjust the three resistances 3, 4 and 5 simultaneously by means of a single control arm, and to shift by steps the condensers 6, 7 and 8 to other condensers, respectively, by means of a multi-pole switch. At higher frequencies, it may 20 be simpler to use continuously variable condensers 6, 7 and 8 operated by a single control arm and to switch by steps the resistances 3, 4 and 5 to other resistances, respectively.

One advantage of such a network is that the 25 frequency may be varied by varying the three resistances or the three condensers, or both. For frequency ranges where it is feasible to vary the resistors, this provides an extremely satisfactory and economical means of control. Such a network 30 may also be modified so that, instead of balancing sharply to an exact null, it provides a small amount of regeneration at essentially the same frequency, thus combining the functions of the regenerative and degenerative networks 35 shown in Fig. 2.

In Fig. 1, the single network may provide sufficient regeneration in the neighborhood of the oscillation frequency to provide sustained oscillations, but sufficient degeneration at other frequencies for satisfactory suppression of harmonics, noise, etc. For instance, if the network 40 shown in Fig. 4 is used in Fig. 1 for the feedback network, its circuit elements may be so selected as to provide the proper characteristics. A further illustration is afforded by Fig. 9 if the 45 adjustable resistor 213 and the condenser 214 in series therewith, as enclosed in the dotted line marked 216, are omitted. This dotted line 216 represents a network that is used to provide regenerative feed-back.

It is illustrated in this case as comprising the elements 213 and 214, with the element 213 in the form of a potentiometer for varying the amount of the feed-back, and with the element 55 214 as a condenser for keeping the plate voltage of the tube 14 off of the grid of tube 12. The elements 213 and 214 represent only one of many possible combinations which could be used as the regenerative feedback network 216. Another 60 possible arrangement is shown in Fig. 11, where the regenerative network 261 is shown consisting of a potentiometer 265 with a slider 267 and a blocking condenser 268. This network may also include a transformer or other types of circuit elements. The networks 9 in Fig. 2 and 217 in Fig. 6 fulfill the same functions as the networks 216 of Fig. 9 and 261 of Fig. 11.

An oscillatory condition may be obtained without a separate regeneration network, for instance, if the resistor 5 is reduced somewhat below the calculated exact value for a perfect null point. A similar effect is obtained by similarly varying the resistors 3 or 4, or condensers 6, 7 or 8, or by varying any of the other components 75 in the proper direction. Fig. 10 shows the varia-

tion in the feed-back voltage obtained from a network of this type. That portion of the curve above the line 350 indicates degenerative feed-back, while that below the line 350 indicates regenerative feedback. The step from Fig. 7 to Fig. 10 is obtained by varying the elements, as 5 described above. This result can be obtained, for instance, with the circuits shown in Figs. 3, 4 and 5, by varying one or more circuit elements 10 in the proper direction away from the values required for exact null balance.

If a separate regenerative feed-back network is employed, there are many possible arrangements. For instance, a transformer may be used to feed sufficient energy from the output of any 15 amplifying stage to the input of the same or a previous stage and in the proper phase to provide sufficient regeneration. If the amplifier comprises three or more stages, a feed-back voltage may be coupled from the output of any of 20 the odd-numbered stages except the first into the input of a preceding even-numbered stage, as shown in Fig. 6, by means of a transformer, voltage divider, or other coupling device, or, if the amplifier comprises two or more stages, the 25 feed-back voltage may be coupled from the output of any of the even-numbered stages into the input of a preceding odd-numbered stage. Fig. 9 shows this latter arrangement, the network 30 216 being connected between the output circuit of the second stage 14 and the input circuit of the first stage 13. As previously pointed out, it is not necessary that the regenerative network 35 be selective as to frequency, but merely that the regeneration voltage, except in the neighborhood of the oscillation frequency, shall be small compared to the degenerative voltage, so that the selectivity characteristic of the combined amplifier and degeneration networks, which characteristics provide the means for obtaining an excellent sinusoidal output wave-form, are not seriously impaired. Of course, a selective regenerative circuit which transmits only in the neighborhood of the oscillation frequency may be employed, but it is not necessary for satisfactory 45 operation of the oscillator.

If the regenerative circuits are so designed that the regeneration is of suitable magnitude over the range of frequencies which the oscillator is intended to cover, the frequency of the oscillator 50 can, accordingly, be adjusted by merely adjusting the degeneration network. Such a network may, for many applications, consist of resistances and capacitances only and variation is a relatively simple matter. The preferred arrangement for 55 low-frequency use is to vary the frequency continuously by controlling the resistances in the degeneration network simultaneously by means of a single control and to vary the frequency in steps by switching various sizes of condensers into and out of the circuit, as illustrated and described in the said copending application. For higher frequencies, it is sometimes more convenient to vary the condensers continuously and the resistances in steps, as is also disclosed therein. At 60 high frequencies a bridged-T network, such as is illustrated in Fig. 5, is also sometimes easier to manufacture or to control than the parallel-T networks.

Fig. 11 shows a further modification of the 70 circuit, in which only two amplifying stages are used, and the necessary phase reversal for degeneration purposes is obtained in the transformer 260. This diagram shows also another possible form of regeneration network 261 com- 75

prising a potentiometer 265 and a condenser 268. The potentiometer 265 is connected in the output circuit of the tube 13 and the condenser 268 is connected between the grid 154 of the tube 12 and the slider 267 of the potentiometer through the resistor 11. This network 261 operates practically the same as the network 216 of Fig. 9. For the sake of variety, the grid biases in this Fig. 11 for the grid 12 of the respective tubes 12 and 13 are shown as separate batteries 269 and 271.

Other modifications and changes will also occur to persons skilled in the art, and all such are considered to fall within the spirit and scope of the present invention, as defined in the appended claims.

What is claimed is:

1. An oscillator having, in combination, an amplifier having an input circuit and an output circuit, a network having a characteristic curve such that the network shall attenuate a predetermined frequency, and means for degeneratively coupling the output circuit to the input circuit to feed back energy from the output circuit to the input circuit through the network, the oscillator comprising means for effecting a reversal of phase between the voltage of the input circuit and the voltage applied to the input circuit by the network and means for providing sufficient regenerative coupling between the output circuit and the input circuit to cause self-oscillation to take place at the said predetermined frequency.

2. An oscillator having, in combination, an amplifier having an input circuit and an output circuit, a network having an input circuit and an output circuit and having a characteristic curve such that the network shall attenuate a predetermined frequency, means for coupling the network input circuit to the amplifier output circuit and the network output circuit to the amplifier input circuit to feed back energy from the amplifier output circuit to the amplifier input circuit through the network, the oscillator comprising means for effecting a reversal of phase between the voltage in the amplifier input circuit and the voltage applied to the amplifier input circuit by the network output circuit, and means for providing sufficient regenerative coupling between the amplifier output circuit and the amplifier input circuit to cause self-oscillation to take place at the said predetermined frequency.

3. An oscillator having, in combination, an amplifier having an input circuit and an output circuit, a three-terminal network having a characteristic curve such that the network shall attenuate a predetermined frequency, means connecting two of the terminals of the network to the output circuit and one of the said two terminals and the third terminal of the network to the input circuit to feed back energy from the output circuit to the input circuit through the network, the oscillator comprising means for effecting a reversal of phase between the voltage in the input circuit and the voltage applied to the input circuit by the network, and means for providing sufficient regenerative coupling between the output circuit and the input circuit to cause self-oscillation to take place at the said predetermined frequency.

4. An oscillator having, in combination, an amplifier having an input circuit and an output circuit, a network having a characteristic curve such that the network shall attenuate a predetermined frequency, and means for degeneratively

coupling the output circuit to the input circuit to feed back energy from the output circuit to the input circuit through the network, the oscillator comprising means for effecting a reversal of phase between the voltage of the input circuit and the voltage applied to the input circuit by the network and means for regeneratively coupling the output circuit through the input circuit at the said predetermined frequency to cause self-oscillation to take place.

5. An oscillator having, in combination, an amplifier having an input circuit and an output circuit, the amplifier comprising a plurality of amplifying stages each having an input circuit and an output circuit, a network having a characteristic curve such that the network shall attenuate a predetermined frequency, means for degeneratively coupling the amplifier output circuit to the amplifier input circuit to feed back energy from the amplifier output circuit to the amplifier input circuit through the network, the oscillator comprising means for effecting a reversal of phase between the voltage of the amplifier input circuit and the voltage applied to the amplifier input circuit by the network, and means for coupling the output circuit of any odd-numbered stage except the first stage to the input circuit of any preceding even-numbered stage to provide sufficient regeneration to cause self-oscillation to take place at the predetermined frequency.

6. An oscillator having, in combination, an amplifier having an input circuit and an output circuit, the amplifier comprising a plurality of amplifying stages each having an input circuit and an output circuit, a network having a characteristic curve such that the network shall attenuate a predetermined frequency, means for degeneratively coupling the amplifier output circuit to the amplifier input circuit to feed back energy from the amplifier output circuit to the amplifier input circuit through the network, the oscillator comprising means for effecting a reversal of phase between the voltage of the amplifier input circuit and the voltage applied to the amplifier input circuit by the network, and means for coupling the output circuit of any even-numbered stage to the input circuit of any preceding odd-numbered stage to provide sufficient regeneration to cause self-oscillation to take place at the predetermined frequency.

7. An oscillator having, in combination, an amplifier having an input circuit and an output circuit, a network having a characteristic curve such that the network shall attenuate a predetermined frequency, the network containing a plurality of resistive impedances and a plurality of capacitive impedances, means for degeneratively coupling the output circuit to the input circuit to feed back energy from the output circuit to the input circuit through the network, the oscillator comprising means for effecting a reversal of phase between the voltage of the input circuit and the voltage applied to the input circuit by the network, means for adjusting a plurality of the impedances, and means for providing sufficient regenerative coupling between the output circuit and the input circuit to cause self-oscillation to take place at the said predetermined frequency.

8. An oscillator comprising an amplifier having an input circuit and an output circuit, means for degeneratively coupling the output circuit to the input circuit, the said means having substantially minimum coupling at a predetermined frequency and comprising a plurality of resistors and capaci-

5 circuit, the amplifier comprising an even number of stages, a network having a characteristic curve such that the network shall attenuate a predetermined frequency, means comprising a transformer for degeneratively coupling the output circuit to the input circuit to feed back energy from the output circuit to the input circuit through the network, and means for providing sufficient regenerative coupling between the output circuit and the input circuit to cause self-oscillation to take place at the said predetermined frequency.

10 18. An oscillator having, in combination an amplifier having an input circuit and an output circuit, a network having a characteristic curve such that the network shall attenuate a predetermined frequency, means for degeneratively coupling the output circuit to the input circuit to feed back energy from the output circuit to the input circuit through the network, the oscillator comprising means for effecting a reversal of phase between the voltage of the input circuit and the voltage applied to the input circuit by the network, means for providing sufficient regenerative coupling between the output circuit and the input circuit to cause self-oscillation to take place at the said predetermined frequency, and means for varying the attenuation of the voltage on the output circuit.

15 19. An oscillator having, in combination, an amplifier having an input circuit and an output circuit, a network having a characteristic curve such that the network shall attenuate a predetermined frequency, means for degeneratively coupling the output circuit to the input circuit to feed back energy from the output circuit to the input circuit through the network, the oscillator comprising means for effecting a reversal of phase between the voltage of the input circuit and the voltage applied to the input circuit by the network, means for providing sufficient regenerative coupling between the output circuit and the input circuit to cause self-oscillation to take place at the said predetermined frequency, and means for varying the gain of the amplifier to vary the wave form of the oscillations.

20 20. An electrical circuit oscillatory at a predetermined frequency and comprising an amplifier having an input circuit and an output circuit, a single network for coupling the output circuit regeneratively to the input circuit at the oscillatory frequency and for degeneratively coupling the output circuit to the input circuit at frequencies removed from the oscillatory frequency by one octave and more, and means for reducing the transmission through said degenerative-coupling means to zero at said predetermined frequency.

25 21. An electrical circuit oscillatory at a predetermined frequency and comprising an amplifier having an input circuit and an output circuit and a single network for coupling the output circuit regeneratively to the input circuit at the oscillatory frequency and for degeneratively coupling the output circuit to the input circuit at all frequencies removed from the oscillatory frequency by one octave and more, the said network having resistive and capacitive impedances only.

30 22. An electrical circuit oscillatory at a predetermined frequency and comprising an amplifier having an input circuit and an output circuit and a single network for coupling the output circuit regeneratively to the input circuit at the oscillatory frequency and for degeneratively coupling the output circuit to the input circuit at all fre-

quencies removed from the oscillatory frequency by one octave and more, the said network having resistive and capacitive impedances only, and means for varying a plurality of the impedances.

35 23. An oscillator having, in combination, an amplifier having an input circuit and an output circuit, means for degeneratively coupling the output circuit to the input circuit so as to reduce the effective gain of the amplifier, the said means comprising a three-terminal network having one terminal common to the input and output circuits and the other two terminals respectively connected to the input and output circuits, means for reducing the transmission through said degenerative-coupling means to a minimum at a predetermined frequency, and means for providing sufficient regenerative coupling between the output circuit and the input circuit to cause self-oscillation to take place at the said predetermined frequency.

40 24. An oscillator having, in combination, an amplifier having an input circuit and an output circuit, means for degeneratively coupling the output circuit to the input circuit so as to reduce the effective gain of the amplifier, the said means comprising a three-terminal network having one terminal common to the input and output circuits and the other two terminals respectively connected to the input and output circuits, means for reducing the transmission through said degenerative-coupling means to zero at a predetermined frequency, and means for providing sufficient regenerative coupling between the output circuit and the input circuit to cause self-oscillation to take place at the said predetermined frequency.

45 25. An electrical circuit, oscillatory at a predetermined frequency and consisting of an amplifier having an input circuit and an output circuit, means for coupling the output circuit regeneratively to the input circuit at the oscillatory frequency, the said means comprising a three-terminal network having one terminal common to the input and output circuits and the other two terminals respectively connected to the input and output circuits, means for degeneratively coupling the output circuit to the input circuit at frequencies removed from the oscillatory frequency by one octave and more, and means for reducing the transmission through said degenerative-coupling means to zero at said predetermined frequency.

50 26. An oscillator comprising an amplifier having an input circuit and an output circuit, means for degeneratively coupling the output circuit to the input circuit, the said means comprising a three-terminal network having one terminal common to the input and output circuits and the other two terminals respectively connected to the input and output circuits, the said means having substantially minimum coupling at a predetermined frequency and comprising a plurality of resistors and capacitors only, means for varying the resistors only to vary the frequency of the oscillations of the oscillator, and means for providing sufficient regenerative coupling between the output circuit and the input circuit to cause self-oscillation to take place at the said predetermined frequency.

55 27. An electrical circuit oscillatory at a predetermined frequency and comprising an amplifier having an input circuit and an output circuit and means for coupling the output circuit regeneratively to the input circuit at the oscillatory frequency and for degeneratively coupling the output circuit to the input circuit at all fre-

the output circuit to the input circuit at frequencies removed from the oscillatory frequency by one octave and more, the said means comprising a three-terminal network having one terminal common to the input and output circuits and the other two terminals respectively connected to the input and output circuits, and means for reducing the transmission through said degenerative-coupling means to zero at the said predetermined frequency.

5 32. An oscillator having, in combination, an amplifier having an input circuit and an output circuit, a network having an input circuit and an output circuit and having a characteristic curve such that the network shall attenuate a predetermined frequency, and means for degeneratively coupling the output circuit to the input circuit to feed back energy from the output circuit to the input circuit through the network, the oscillator comprising means for effecting a reversal of phase between the voltage of the input circuit and the voltage applied to the input circuit by the network, and the network comprising means for providing sufficient regenerative coupling between the output circuit and the input circuit to cause self-oscillation to take place at the said predetermined frequency.

10 33. An oscillator having, in combination, an amplifier having an input circuit and an output circuit, the amplifier comprising a plurality of amplifying stages each having an input circuit and an output circuit, a network having a characteristic curve such that the network shall attenuate a predetermined frequency, means for degeneratively coupling the amplifier output circuit to the amplifier input circuit to feed back energy from the amplifier output circuit to the amplifier input circuit through the network, the oscillator comprising means for effecting a reversal of phase between the voltage of the amplifier input circuit and the voltage applied to the amplifier input circuit by the network, and means for providing sufficient regenerative coupling in the amplifier so that self-oscillation shall take place at the predetermined frequency.

15 34. An oscillator having in combination an amplifier having an input circuit and an output circuit, a network having a characteristic such that it attenuates a predetermined frequency, means for degeneratively coupling the amplifier output circuit through the network to the amplifier input circuit, the total phase shift through the amplifier and degenerative coupling circuits being such that the application of an alternating voltage to the input circuit of the amplifier from an external source shall result in the application 20 to the same circuit by the feed-back circuit of a voltage of the same frequency but opposing in phase, and means for providing sufficient regenerative coupling so that self-oscillation shall take place at said predetermined frequency.

25 35. An oscillator having, in combination, an amplifier having an input circuit and an output circuit, a network having a characteristic curve such that the network shall attenuate a predetermined frequency, means for degeneratively coupling the output circuit to the input circuit to feed back energy from the output circuit to the

30 36. An electrical circuit oscillatory at a predetermined frequency and comprising an amplifier having an input circuit and an output circuit and a single three-terminal network for coupling the output circuit regeneratively to the input circuit at the oscillatory frequency and for degeneratively coupling the output circuit to the input circuit at frequencies removed from the oscillatory frequency by one octave and more, the said network having one terminal common to the input and output circuits and the other two terminals respectively connected to the input and output circuits, and means for reducing the transmission through said degenerative-coupling means to zero at the said predetermined frequency.

30 37. An electrical circuit oscillatory at a predetermined frequency and comprising an amplifier having an input circuit and an output circuit and a single three-terminal network for coupling the output circuit regeneratively to the input circuit at the oscillatory frequency and for degeneratively coupling the output circuit to the input circuit at frequencies removed from the oscillatory frequency by one octave and more, the said network having one terminal common to the input and output circuits and the other two terminals respectively connected to the input and output circuits, and the said network having resistive and capacitive impedances only.

35 38. An electrical circuit oscillatory at a predetermined frequency and comprising an amplifier having an input circuit and an output circuit and a single three-terminal network for coupling the output circuit regeneratively to the input circuit at the oscillatory frequency and for degeneratively coupling the output circuit to the input circuit at frequencies removed from the oscillatory frequency by one octave and more, the said network having one terminal common to the input and output circuits and the other two terminals respectively connected to the input and output circuits, the said network having resistive and capacitive impedances only, and means for varying a plurality of the impedances.

40 39. An oscillator having, in combination, an amplifier having an input circuit and an output circuit, a network having a characteristic curve such that the network shall attenuate a predetermined frequency, means for degeneratively coupling the output circuit to the input circuit to feed back energy from the output circuit to the
